(57) **CLAIM**

The ornamental design for a welder enclosure, as shown and described.

DESCRIPTION

FIG. 1 is a front perspective view of a welder enclosure showing our new design;

FIG. 2 is a further front perspective view thereof;

FIG. 3 is a rear perspective view thereof;

FIG. 4 is a further rear perspective view thereof;

FIG. 5 is a further rear perspective view thereof;

FIG. 6 is a further rear perspective view thereof;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof; and,

FIG. 12 is a bottom plan view thereof.

The broken lines immediately adjacent the shaded areas represent the bounds of the claimed design while all other broken lines are directed to portions of a welder enclosure that forms no part of the claimed design.

1 Claim, 12 Drawing Sheets
